DESIGN FOR A VANITY CASE OR THE LIKE

Alfred F. Reilly, North Attleboro, Mass., assignor to Evans Case Company, a corporation of Massachusetts

Application May 21, 1937, Serial No. 69,474

Term of patent 3½ years

To all whom it may concern:

Be it known that I, Alfred F. Reilly, a citizen of the United States, residing at North Attleboro, county of Bristol, and State of Massachusetts, have invented a new, original, and ornamental Design for Vanity Cases or the like, of which the following is a specification, reference being had to the accompanying drawing, forming a part thereof.

In the accompanying drawing Figure 1 is a top plan view of a vanity case showing my new design. Fig. 2 is a bottom plan view of a vanity case showing my new design. Fig. 3 is a front elevation of a vanity case showing my new design.

I claim:

The ornamental design for a vanity case or the like as shown.

ALFRED F. REILLY.
